DISPLAY FIXTURE

George D. Melas, Salinas, Calif.

Application April 26, 1930, Serial No. 447,615
Renewed May 15, 1933

9 Claims. (Cl. 211—154)

This invention relates to improvements in apparatus for displaying wearing apparel and furnishings in windows and other parts of stores.

An object of the invention is to provide display equipment of the character described which is capable of being easily set and taken down and adjusted in various ways to best display the particular article or articles supported thereon.

Another object of the invention is to provide a display receiving plate or base of novel form and arrangement which can be readily attached to various types of stands and tilted or revolved to any desired display position either before or after the mounting thereon or the securing there-

to of hats, caps, shirts, underwear, hosiery, sweaters, shoes and other apparel to be displayed. Another object is to provide a novel hat display fixture which is readily attachable to and removable from the display plate and serves in a most effective manner in combination with said plate to hold and display hats, caps and the like without leaving objectionable marks, creases or the like, or in any way marring the appearance of the hat.

A further object of my invention is to provide display equipment of the character described with which display boards or forms of various sizes and shapes, and such as used for trimming shirts, sweaters, underwear, hosiery and the like, may be easily and quickly placed on and secured to the display receiving plate, either before or after trimming such boards or forms and without the use of wire cord or other makeshift fastening means, said forms or boards being also quickly and easily detachable from the said plate and the plate and board or form being likewise readily removable from the stand.

Still another object is to provide a display receiving base or plate which serves as a foundation for a quick and easy attachment or removable fixation thereto or the positioning thereon of display forms and articles of apparel of various kinds without the use of wire, cord or other extraneous fastenings and thereby as one unit and in a particularly efficient manner meets practically all display fixture requirements of substantially all window dressing and store display operations relating to wearing apparel and the like.

The invention possesses other objects and features of advantage, some of which, with the foregoing, will be set forth in the following description of the preferred form of the invention which is illustrated in the drawing accompanying and forming part of the specification. It is to be understood, however, that variations in the show-

ing made by the said drawing and description may be adopted within the scope of the invention as set forth in the claims.

Figure 1 represents a side elevation of the display fixture of my invention shown on a stand 60 and with a hat display form thereon.

Figure 2 is an enlarged top plan view of the fixture showing the hat form thereon, the dotted line indicating the outline of the crown of the hat.

Figure 3 is a sectional view on the plane of line 3—3 of Figure 2 showing the manner of attaching the hat form to the fixture plate.

Figure 4 is a side elevation showing the fixture as when supporting a display board or plate used 70 to display shirts, underwear and like garments.

The fixture of my invention as shown in detail in the accompanying drawing essentially includes a display supporting a base plate 1 of flat, thin sheet material, such as sheet steel or other suitable metal, and is generally of rectangular outline. In the center of the plate is a depression 2 forming a projection 3 on the rear side, which projection is adapted to frictionally fit within a depression 4 formed in the flat circular head 5 80 of an attaching bracket 6. A screw 7 is inserted through an opening 8 in the center of the plate depression 2 and may be screwed tight within a screw threaded opening 9 in the head 5 of the bracket 6. This screw, it will be noted, serves 85 as a pivot mounting for the plate 1 permitting the plate to be turned or rotated as desired. However, on tightening of the screw the plate 1 may be clamped and held in any position of adjustment thereof. Furthermore this means of 90 connection of the plate and bracket permits of a ready and easy attachment and detachment of the plate 1 relative to said bracket.

An apertured ear 10' on the bracket 6 provides for the usual pivotal connection of the bracket 95 with the upper end of a stand 11 such as commonly used in display equipment, there being a horizontal screw 10' providing for such pivotal connection, and for a setting of the pivot to hold the bracket in various adjusted position.

It will now be seen that with the plate pivoted on the bracket for rotary movement and the bracket pivoted on a horizontal axis upon the stand, the plate may be disposed in various display positions as desired and best suited to the 105 article display, and may be readily set or locked in the desired position of adjustment.

With the plate and bracket 6 comprising a display unit it is clear that such a unit may be quickly and easily attached to and removed from 110

various kinds of display stands or racks as desired. Owing to the construction of the said plate, as will hereinafter be fully described, the unit will serve as means for supporting various articles to be displayed and for a quick detachable connection therewith of various kinds of hat, shirt and other forms on which such garments are arranged for display.

As here shown the plate 1 is provided on opposite sides of its center mounting with keyhole slots or openings 14 and 15, the longitudinal axes of which are on the longitudinal center line of the plate. Such openings are adapted for attachment of a hat form generally designated 16 or for a shirt form 17 or for various other forms not shown. It being now clear that any such forms equipped with headed or even non-headed lugs or projections such as the ones 18 on the shirt form 17, which lugs will removably fit and lock in said keyhole slots in the usual manner, may be readily and easily attached to the base plate 1 of my invention. In the ends of the plate 1 are slots 19 and 20 formed between rounded ear like projections 21 and 22. These ears or projections lend ornamentation to the plate and serve as hangers or members on which articles may be hung or fitted to be displayed. The slots 19 and 20 permit of hooking or of fitting the lugs or other parts of display forms to the plate whereby to hold the forms. It is preferable to make the slots 19 and 20 of the same width as the narrower parts of the keyhole slots 14 and 15, whereby the lugs or projections which fit in said keyhole slots may also be fitted in the said end opening slots inasmuch as in some instances of display arrangements the use of the slots 19 and 20 may be preferable.

The hat form 16 comprises a substantially T shaped attaching and body member 24 from the free end of the shank portion 25 of which a T shaped lug 26 is formed to extend at right angles to the shank. At the center of the head portion of the member 24 is a lug 27 extending at right angles to the shank in the same direction and manner as the lug 26. These lugs are adapted to fit in either of the slots 14 and 15 with the headed lug 26 so engaged in the slot as to prevent outward displacement of the member 24. The other lug 27 acts as a stop and engages with one end of the slot and also prevents lateral displacement of the member 24. The larger portions of the keyhole openings permit of ready insertion and removal of said lugs.

The hat form or holder itself, as here shown, is made of wire bent to form straight and parallel plate engaging portions 28 and 29 arranged to extend transversely of the plate 1. At the outer ends of the portions 28 and 29 are outwardly extending portions 30 which at their outer ends are joined by bowed but engaging portions 31 and 32 arranged to be disposed adjacent and lengthwise of the opposite longitudinal edges of the plate 1. The portion 28 is in two sections, each clamped upon the T shaped holder by means of bent over portions 33 of said holder forming tubular guides and clamps for said sections. Joined with the sections of the wire portion 28 are outwardly diverging arms 34 arranged to lie upon the outer face of the plate 1 and to extend toward an adjacent end of the plate. Similar bent over socket and clamp members 35 are formed on the shank 25 and embrace the arms 34. At their outer ends of the arms 34 the wire is bent first outward to define the portions 36 corresponding to the portions 30, and the por-

tions 36 are joined by a bowed portion 7 disposed in the same plane as the portions 31 and 32 but between and at right angles thereto. The portions 31 and 32 and the portion 37 also the portions 30 and 36 are disposed to extend into and conform to the curvature of the crown of a hat and will engage the inside of the hat in such manner as to hold the hat in place without leaving a mark on the outer side of or misshapening the hat in any manner and permit the under side of the hat to lie flat against the plate 1. I have found that a hat holder of this form made of light resilient wire will serve effectively to hold a hat, cap, or the like in place without damaging or marking the hat and in such manner that the form or holder will be effectively concealed. It will be seen that such a hat form may be quickly attached to the plate 1 either before or after a hat is mounted thereon and may be as readily and easily removed when desired or that the hat may be readily removed from the form without necessitating removal of the latter from the plate 1. This also applies with equal force to the shirt form 17 and any other form which may be attached to the plate 1 as hereinbefore described.

I claim:

1. In a display fixture, a plate-like member, a bracket on which said member is adjustably supported, means providing for adjustably connecting the bracket with a stand, interfitted portions on plate and bracket and a member adjustably joining said plate and bracket and passing through said interfitted portions.

2. In a display fixture, a plate-like member, a bracket on which said member is adjustably supported, means providing for adjustably connecting the bracket with a stand, interfitted portions on plate and bracket and a screw member pivotally joining said plate and bracket and passing through said interfitted portions and providing for holding the plate in adjusted position.

3. In a display fixture, a plate member having a depression on its front side forming a projection on its rear side, a bracket, a flat head portion on the bracket arranged to engage the rear face of the plate member, said head portion having a depression therein in which said projection is engaged, and a screw passing through the plate and threadedly engaged with said head portion in such manner as to prevent the turning of the plate on the screw and the holding of the plate against turning.

4. In a display fixture, a plate member, a bracket for attaching said member to a stand, said plate having a keyhole slot therein for reception of a display form carried projection whereby to removably secure such a form to the plate.

5. In a display fixture, a rectangular plate member, and bracket for securing said member to a stand and to which the plate is centrally pivoted, said plate having a keyhole opening therein in line with the pivotal connection of the bracket and plate and on the longitudinal axis of said plate.

6. In a display fixture a plate, a bracket for securing said plate to a stand and to which the plate is pivoted at a point adjacent to its center, and projections at opposed edges of said plate defining slots therebetween, said plate having elongated openings therein disposed on opposite side of the pivot point.

7. In a display fixture, a plate, means for attaching said plate to a stand, and a hat displaying and supporting form detachably carried by said plate and comprising spaced bars arranged

in outwardly spaced and substantially parallel relation to the opposed face of the plate and adapted to fit within the crown of the hat with the latter lying flat against the plate.

- 5 8. In a display fixture, a plate, means for attaching said plate to a stand, a hat displaying and supporting form detachably carried by said plate and comprising outwardly bowed spaced bars arranged in outwardly spaced and substantially parallel relation to the opposed face of the plate and adapted to fit within the crown of the hat

with the latter lying flat against the plate, certain of said bars lying in opposed relation to one another, and another of said bars lying at right angles to and between the first-named bars.

9. In a display fixture, a plate, means for attaching said plate to a stand, and a hat displaying and supporting form carried by said plate, a form holder plate having a slot therein and lugs on the form holder arranged to engage in said slot.
